TRANSPARENCY STORAGE AND CARRYING CASE

Hiram L. Mills, Prairie Village, Kans.

Application July 3, 1956, Serial No. 42,131

Term of patent 14 years

(Cl. D87—5)

Fig. 1.

Fig. 2.

Fig. 3.

Fig. 1 is a perspective view of a transparency storage and carrying case embodying my new design, the lid being shown in partly open condition;

Fig. 2 is a perspective view of same in closed condition, showing the opposite end and side of the case; and

Fig. 3 is a bottom plan view of same.

I claim:

The ornamental design for a transparency storage and carrying case, as shown.
